DESIGN FOR A DISPLAY PLATE FOR AUTOMOBILES OR THE LIKE

Myron A. Quigley, Canton, Ill.

Application April 1, 1942, Serial No. 106,415

Term of patent 3½ years

To all whom it may concern:

Be it known that I, Myron A. Quigley, a citizen of the United States, residing at Canton, in the county of Fulton and State of Illinois, have invented a new, original, and ornamental Design for a Display Plate for Automobiles or the like, of which the following is a specification, reference being had to the accompanying drawing, forming a part thereof.

I claim:

The ornamental design for a display plate for automobiles or the like, as shown.

MYRON A. QUIGLEY.
